SWIMMER'S FLOAT OR THE LIKE

William M. Saeman, 433 S. Mary St., Sunnyvale, Calif.

Filed June 5, 1959, Ser. No. 56,219

Term of patent 7 years

(Cl. D71—1)

Fig. 1 is a top perspective view of a swimmer's float or the like showing my new design;

Fig. 2 is a side elevation thereof.

The bottom is the same in appearance as the top.

The dominant features of the design reside in the portions shown in full lines.

I claim:

The ornamental design for a swimmer's float or the like, substantially as shown and described.
